COMBINATION LOCK FOR STEERING WHEELS.

1,412,022.

Specification of Letters Patent.

Patented Apr. 4, 1922.

Application filed November 25, 1919. Serial No. 340,537.

To all whom it may concern:

Be it known that I, MARK A. WHITTLE, citizen of the United States, residing at San Francisco, in the county of San Francisco, 5 State of California, have invented a new and useful Combination Lock for Steering Wheels, of which the following is a specification, in such full and clear terms as will enable those skilled in the art to construct 10 and use the same.

This invention relates to a combination lock for steering wheels or for other uses to which it may be adapted which may be operated either by the visual method or by 15 listening to a clicking pin as the tumblers are rotated in which means is provided to prevent unauthorized persons from holding the lock bolt against the tumblers and feeling the notches in the tumblers to discover the 20 combinations.

Another object of the invention is to provide means whereby the operator can open the lock without turning the tumblers more than once or twice, thereby enabling the lock 25 to be opened quickly.

Another object of the invention is to provide means whereby the bolt may be extended to the locked position by rotating the tumbler operating knob.

30 Other objects of the invention will appear as the description proceeds.

An embodiment of the invention is shown in the accompanying drawings in which the same reference numeral is applied to the 35 same portion throughout, but I am aware that there may be modifications thereof.

Fig. 1 is a vertical sectional view of the lock in use,

Fig. 2 is a side elevation of the filler which 40 carries the bolt,

Fig. 3 is a sectional view on the line 3—3, Fig. 1,

Fig. 4 is a plan view of the lock, and

Fig. 5 is a view of the steel plate used 45 for giving audible signals to open the lock.

The lock comprises a casing 1 which has the operating knob 2 on one side and it is provided with a curved seat on the other side for the steering column 3, a clamp 4 being 50 used to secure the lock to the steering column just under the hub 5 of the steering wheel 6.

The clamp is secured to the lock and

column by means of suitable screws 7 which have notches in their heads for rotating them 55 in one direction only.

The lock casing is cored out to receive a filler 8 which carries the bolt 9 and also to provide a space for the three tumblers 10, 11 and 12, operating pin 13, and the bolt 60 pin 14.

The operating pin has the tumbler 10 rigidly connected thereto and it is connected to the knob 2 by means of a pin 15.

Washers 16, 17 hold the tumblers apart 65 to provide for the operation of the loose tumblers 11 and 12.

The tumblers 10 and 11 are each provided with two pins as indicated at 18 to 70 inclusive to operate the pins 22, 23 on the tumblers 11, 12 respectively, the object of providing two pins being to reduce the number of times the knob must be turned around to place the tumblers in the unlocking 75 position.

The pin 14 falls into the notches in the tumblers when they are aligned under it, but when they are not aligned under it, it rides on the tumbler 10 which is higher than the others until its notch happens to come under the pin whereupon it will drop into the notch and prevent further rotation of any of the tumblers. The pin 14 when dropped into the slot of the disk 10 prevents 80 the rotating of the remaining tumblers because the disk 10 is rigidly connected to the pin 13 with which the other tumblers are rotated.

In order to frictionally hold the tumblers 11 and 12 in any position they are each provided with a light spring as shown at 24, 25 and in order to provide for operating the combination in the dark, there is a hardened ring 26 let into the back of the knob. This ring has a plurality of ridges thereon with an extended smooth place 27 which is the starting place for operating the combination. The hardened ring 26 is for the purpose of audibly detecting the operation of the two smaller tumblers. The lock body has a hole therein to receive a pin 26' which pin is projected therefrom by means of a small spring 26'' so that as the ring 26 is rotated the pin 26' will snap over the ridges and in that way enable the person operating the 105 lock to open it in the dark.

The lock bolt has a pin 28 which enables the cam 29 to throw the bolt up by the rotation of the knob 2.

The lock is secured to the steering column 5 by inserting the screws 7 through the holes in the clamp 4. A hole is previously bored in the hub 5 of the steering wheel in such a position as to receive the bolt 9. The bolt 9 is pushed up by the cam 29 bearing upon 10 the pin 28. So long as the disks 10, 11 and 12 are not in a position to permit the pin 14 connected to the bolt 9 to move downwardly to the bottom of the slots in the disks 11 and 12, the bolt cannot be retracted 15 sufficiently to rotate the steering wheel. When the pin 13 is rotated if the bolt 9 is not held up the weight of the bolt 9 will cause it to drop down with its pin 14 in the slot of the disk 10. This will at once prevent further rotation of any of the disks 20 because the pin 13 will be stopped and this feature prevents experts from feeling the position of the notches in the disks 11 and 12 and thereby unauthorizedly opening the lock.

In order to open the lock the bolt must be held up as illustrated in Figure 1 by the operator pushing on the bottom of the bolt 9 with his finger. Thereupon the two disks 11 and 12 will be set to the desired position 30 they are to occupy in accordance with the combination; after which the disk 10 is set with its slot in alignment with the two slots in the disks 11 and 12; thereupon the bolt 9 may be retracted so as to be disengaged 35 from the hub 5. The cam 29 will project the bolt 9 if rotated in one direction and will prevent the rotation of the pin 13 unless the bolt 9 is held up.

What I claim is as follows, but various 40 modifications may be made in the construction shown in the drawings and above particularly described form, within the purview of my invention:

1. A lock for automobile steering wheels 45 comprising a casing adapted to be secured to a steering column, a bolt carried thereby

capable of being extended into a notch in the steering wheel hub, a pin carried by said bolt, an operating knob, a notched tumbler connected to the knob, a cam carried by said tumbler to extend the bolt, other notched tumblers of less diameter than the first tumbler, means on the tumblers to engage the tumbler rotating mechanism and capable of aligning the several tumbler notches with 50 the notch in the first tumbler, the pin in the bolt preventing the rotation of all of the tumblers unless the bolt is raised.

2. A lock for automobile steering wheels comprising a casing adapted to be secured to 60 a steering column, a bolt carried thereby and slideable into engagement with a notch or hole in the steering wheel hub, an operating knob, a notched tumbler rigidly connected to the knob, notched tumblers of less diameter than the first tumbler movable with the knob and capable of having their notches align with the notch in the larger tumbler, a pin carried by the bolt to prevent the rotation of the tumblers except when the bolt is lifted and audible means to permit the operation of the lock when the combination cannot be seen.

3. A lock for automobile steering wheels comprising a casing adapted to be secured 75 to a steering column, a slideable bolt carried thereby capable of being extended entirely through the casing, an operating knob, a notched tumbler rigidly connected to the knob, other smaller notched tumblers, means to engage the tumblers with said knob whereby all of the tumblers may have their notches aligned, a pin carried by the bolt to prevent the operation of the tumblers except when the bolt is raised with the pin out of 80 engagement with the tumblers and a cam to extend the bolt when the knob is turned in one direction and to prevent the rotation of the tumblers if turned in the opposite direction.

MARK A. WHITTLE.
